UNITED STATES PATENT OFFICE.

WILLIAM H. DUNKERLEY, OF PATERSON, NEW JERSEY.

BRAIDING-MACHINE.

1,213,601.

Specification of Letters Patent. Patented Jan. 23, 1917.

Application filed April 8, 1916. Serial No. 89,767.

To all whom it may concern:

Be it known that I, WILLIAM H. DUNKERLEY, a citizen of the United States, residing at Paterson, in the county of Passaic and State of New Jersey, have invented a certain new and useful Improvement in Braiding-Machines, of which the following is a specification.

The object of the invention is to provide a machine for producing a braided annulus, as a tire or analogous article, in continuous layers with a coating of rubber or the like upon or between such layers, and also to provide means for supporting and rotating the annular form or core during the braiding operation, and for removing such core and its annulus after the braiding and coating operation is completed.

The invention consists in certain novel features and details of construction and arrangement by which the above objects are attained, to be hereinafter described.

The accompanying drawings form a part of this specification and show an approved form of the invention.

Figure 1 is a front elevation of the machine, with a portion of the driving mechanism omitted. Fig. 2 is a side elevation. Fig. 3 is a plan view partly in horizontal section. Fig. 4 is a face or side view showing a form or core alone. Fig. 5 is a plan view of the table and raceways, showing the opening or channel through which the annulus and core are removed from the machine after the completion of the operation.

Similar letters of reference indicate the same parts in all the figures.

A is the bed plate of the machine, supported on a frame or standard B at one side and legs A¹ A¹, and having a table A² above in which are the circularly-arranged serpentine raceways a for the dolls or braiding-carriers G G which are traversed therein by the gearwheels C¹ C¹ and connected mechanism mounted between the table and bed plate, and operating in a manner similar to the usual driving mechanism employed in machines of this character.

In the center of the bed plate and table is an opening a¹ within the circle of the raceways, and both are equipped with a removable portion carrying its part of the raceways and traversing mechanism, shown as a sector A³ which when removed offers an opening or channel reaching from the

exterior to the central hole a¹ through which a core may be introduced and removed with its braided covering. On the standard B are two deeply grooved wheels B¹ B¹ mounted on short horizontal shafts B² B² extending through the standard, each carrying at its opposite end a worm-wheel B³ in mesh with a worm D¹ on a worm-shaft D by which the grooved wheels are rotated.

In the upper part of the standard, and located centrally between the grooved wheels B¹ B¹ below, is mounted a similar wheel or grooved roller E¹ carried on a stud E in a block E² arranged to be moved vertically in an opening b in the standard and held in the desired elevated position by a thumb-nut or handwheel E³ on the screw-threaded end of the stud or shaft E. A spring E⁴ above the block serves to press the latter and its roller gently downward when the grasp of the hand-wheel is relaxed. The roller E¹ is rotated in unison with the rollers B¹ B¹ by means to be described.

L¹ is a drum mounted on the frame with liberty to revolve on a horizontal shaft L², adapted to carry a web L of rubber wound thereon and deliver such web upon the braided surface of the annulus to inclose the latter and to be itself inclosed by the succeeding layer braided thereon, so that the annulus is composed of alternate layers of braided fabric and rubber each a continuous layer.

The end of the web is attached to the first completed braided layer and is then automatically unwound and drawn off from the drum as the braiding operation continues.

The grooved wheels and roller support an annular form or core in a vertical position, and are so located relatively to the central opening a¹ in the table and bed plate as to permit the core when rotated to traverse such opening with sufficient space between its inner surface and the standard to permit the carriers C C to pass freely in the operation of braiding a covering upon the core. The core M is shown as an annulus cut radially at two places m m and provided with hinges at M¹ M¹, and is also cut diagonally as at m¹ to permit the core to be partially collapsed or folded inwardly. It is held in the distended condition by any suitable locking means, shown as a screw at M² joining the beveled ends at the diagonal cut m¹.

By removing the sector A^3 and raising the roller E^1 the core is introduced into the central opening α^1 and yieldingly held in this position on the grooved wheels B^1 B^1 5 when the roller is released. The sector or removable filling-piece A^3 is then replaced, supported by its lugs A^4 A^4 and latch A^5 , with its traversing-gears in mesh and its portion of the raceways matching to those 10 adjacent on each side. The braiding mechanism is then set in motion and the core slowly rotated by means to be described, thus applying a braided covering thereon. In the manufacture of tires the completed 15 covering or layer is coated with rubber as above described, and another layer braided thereon which in turn receives a coating of rubber, and so on until a sufficient number of layers have been braided to produce the 20 desired thickness, the yielding roller E^1 correspondingly rising and rotating in unison with the supporting rollers or wheels as the diameter of the braided annulus increases. The machine is then stopped, the 25 filling-piece A^3 with its connections, removed, and the annulus withdrawn through the channel thus provided. The braided covering with its layers of rubber is then slit along the inner line of the annulus, 30 the screw M^2 removed to permit the core to be collapsed and withdrawn; the cut edges of the annulus may be treated in any suitable manner to preserve and shape them and the whole vulcanized to serve as the body 35 of a tire. In a tire thus manufactured the body is of uniform thickness throughout and the threads laid with equal tension, a result which cannot be attained by wrapping bias strips of fabric upon an annular 40 core as in the usual process, and the threads and rubber are incorporated into a homogeneous mass without air-spaces.

The braiding mechanism and the feeding or rotating means for the core may be 45 driven in any approved manner. As shown in the drawings, F is a horizontal stud on which is mounted a driving wheel F^1 carrying a beveled gearwheel F^2 in mesh with a sliding beveled gearwheel G^2 splined on a 50 vertical shaft G below the stud F . On the shaft G is a gearwheel G^1 in mesh with one of the braiding gearwheels C^1 to drive the braiding mechanism, and at its lower end is a beveled pinion G^3 in mesh with a 55 beveled gearwheel D^3 on a worm-shaft D to impart the required slow motion to the grooved wheels B^1 B^1 which rotate the core.

The sliding beveled gearwheel G^2 is raised 60 to engage the beveled gearwheel F^2 , and thus revolve the vertical shaft G , by a lever H fulcrumed to the bed plate at h and having a handle H^1 , and an arm H^2 extending upwardly and terminating in a hook H^3 65 adapted to be engaged by a swinging dog

J pivoted upon the table A^2 at j . When the lever is raised and the hook thus engaged and held, the mechanism is driven, and when the dog J is swung to release the hook H^3 the beveled gearwheel G^2 drops out of 70 mesh with the wheel F^2 and the mechanism stops. This release may be effected by hand when desired and may also be effected automatically by the descent of the tension weight C^2 of any of the carriers C , which when thus permitted to fall by the breaking of a thread, will strike the dog J in traversing the raceway adjacent to the latter, and move it sufficiently to disengage the hook and thus stop the revolution of 80 the shaft C . On the upper end of the shaft is a crank G^4 by which the machine may be turned by hand in making any desired changes or adjustments.

The upper roller E^1 is driven in the same 85 direction and at the same rate as the supporting wheels B^1 B^1 . Any suitable gearing or driving means may be employed to communicate motion to the upper roller; that shown consists of a beveled gearwheel, 90 as K^1 on one of the shafts B^2 , in which meshes a corresponding beveled wheel K^2 on a vertical shaft K carrying at the lower end a beveled wheel K^3 in mesh with a beveled wheel K^4 on a horizontal shaft K^5 95 carrying on its outer end a beveled gearwheel K^6 meshing with a corresponding wheel N^1 on a vertical shaft N . The latter passes through the laterally extended arms E^3 on the block E^2 , which serve as a retaining yoke for a worm N^2 splined upon the shaft N so that the worm will move with the block and rise or sink on the shaft N while maintaining its engagement with a wormwheel E^6 on the upper roller E^1 . The 100 gearing is so proportioned and arranged as to drive the upper roller in the same direction and at the same speed as the supporting rollers B^1 B^1 . This arrangement permits the upper roller E^1 to rise as the annulus increases in size due to the application of successive layers while maintaining the same speed as such annulus and thus tends to press the web L of rubber smoothly and evenly upon the braided surface. 105

Although the invention is described as applied to the manufacture of tires it will be understood that any article of annular form may be braided, and the core may be of any material, and constructed for removal from the completed article, or to remain permanently inclosed therein.

I claim:—

1. In a braiding machine, a table having a central opening and raceways encircling 110 such opening, braiding-carriers in such raceways, means for moving said braiding-carriers, means for supporting an annular core passing through such central opening and arranged therein to receive a braided cov. 115

ering applied by said braiding-carriers, and means for applying a web of rubber, to such braided covering.

2. In a braiding machine, a table having a central opening and raceways encircling such opening, braiding-carriers in such raceways, means for moving said braiding-carriers, means for supporting an annular core passing through such central opening and arranged therein to receive a braided covering applied by said braiding-carriers, means for rotating such core, and means for applying a web of rubber, to such braided covering.
- 15 3. In a braiding machine, a table having a central opening encircled by raceways and having a channel from the exterior of said table to said central opening, means for supporting an annular core passing through such central opening and arranged therein to receive a braided covering applied by a series of braiding-carriers in said raceways, such channel adapted to allow the removal of such covered core, and means for applying a web of rubber, to such braided covering.

4. In a braiding machine, a table having a central opening and raceways encircling such opening, and having a channel from the exterior of said table to said central opening, braiding-carriers in such raceways, means for moving said braiding-carriers, an annular core passed through such central opening and arranged therein to receive a braided covering applied by said braiding-carriers, wheels supporting said core, means for revolving said wheels and rotating said core, and means for applying a web of rubber upon said covering.

- 40 5. In a braiding machine, a table having a central opening and raceways encircling such opening, braiding-carriers in such raceways, means for moving said braiding-carriers, an annular core passed through such central opening and arranged to receive a braided covering applied by said braiding-carriers, wheels supporting said core, means for revolving said wheels and rotating said core, a roller arranged to press said core yieldingly upon said wheels, and means for applying a web of rubber, to such braided covering.

6. In a braiding machine, a table having a central opening and raceways encircling such opening, braiding-carriers in such raceways, means for moving said braiding-carriers, an annular core passed through such central opening and arranged to receive a braided covering applied by said braiding-carriers, wheels supporting said core, means for revolving said wheels and rotating said

core, a roller arranged to press said core yieldingly upon said wheels, means for applying a web of rubber to such braided covering, and means for revolving said roller in the same direction and at the same rate as said wheels.

7. In a braiding machine, a table having a central opening and raceways encircling such opening, braiding-carriers in such raceways, means for moving said braiding-carriers, an annular core passed through such central opening and arranged to receive a braided covering applied by said braiding-carriers, wheels supporting said core, means for revolving said wheels and rotating said core, a roller arranged to press said core yieldingly upon said wheels, means for revolving said roller in the same direction and at the same rate of speed as said wheels, and a drum adapted to carry a web of rubber and deliver such web upon said braided covering.

8. In a braiding machine, a table having a central opening and raceways encircling such opening, braiding-carriers in such raceways, means for moving said braiding-carriers, an annular core passed through such central opening and arranged therein to receive a braided covering applied by said braiding-carriers, wheels supporting said core, means for revolving said wheels and rotating said core, automatically operated means for stopping the rotation of said core and the movements of said braiding-carriers, and means for applying a web of rubber to said braided covering.

9. In a braiding machine, a table having a central opening and raceways encircling such opening, means for supporting an annular core passing through such central opening, braiding-carriers in such raceways adapted to apply a continuous braided covering upon said core in successive layers, and means for applying a continuous web of rubber in successive layers upon said braided covering and alternating with the layers of such covering.

10. In a braiding machine, a support having an opening and raceways encircling said opening with a channel from the exterior of said support to said opening, braiding-carriers in said raceways, means for moving said braiding-carriers, an annular core passed through said opening and arranged therein to receive a braided covering applied by said braiding-carriers, rotary core-supporting means, and means for applying a web of rubber upon said braided covering.

In testimony that I claim the invention above set forth I affix my signature.

WILLIAM H. DUNKERLEY.
